(57) **CLAIM**

The ornamental design for an air boat cover, as shown and described.

DESCRIPTION

FIG. 1 is a perspective front right side view of an air boat cover in accordance with the present invention;

FIG. 2 is a perspective rear left side view of the air boat cover of FIG. 1;

FIG. 3 is a top plan view of the air boat cover of FIG. 1; FIG. 4 is a bottom plan view of the air boat cover of FIG. 1;

FIG. 5 is an elevational rear view of the air boat cover of FIG. 1;

FIG. 6 is an elevational front view of the air boat cover of FIG. 1;

FIG. 7 is a left-side elevational view of the air boat cover of FIG. 1; and,

FIG. 8 is a right-side elevational view of the air boat cover of FIG. 1.

The broken lines showing a base of an air boat and a pair of engines depict environment only and form no part of the claimed design.
